UNITED STATES PATENT OFFICE.

ALFRED F. MASURY, OF NEW YORK, N. Y., ASSIGNOR TO INTERNATIONAL MOTOR COMPANY, OF NEW YORK, N. Y., A CORPORATION OF NEW JERSEY.

WINDOW.

Application filed September 9, 1925. Serial No. 55,359.

This invention has to do with the windows or closures for the ventilating ports in what are known as monitor type roofs for passenger carrying vehicles, that is, roofs wherein a portion thereof is formed as a vertical wall provided with a plurality of ports whereof some of the closures are adapted to open forwardly to induce a flow of air into the interior of the conveyance while others of the closures are adapted to open rearwardly to permit a flow of air out of the vehicle and induce a reduction of pressure therein whereby the inflow of air at the forward part of the vehicle is facilitated. The present invention has for an object to provide a closure for a ventilating port of the character described which shall be capable of opening in opposite directions to facilitate either the admission of fresh air or the escape of used air. Accordingly means are provided whereby the closure may be moved with respect to the port whereby either one of opposed edges may be disposed in spaced relation from the edge of the closure. More particularly a pane of glass may serve as the closure for a window opening and may be provided upon opposed edges with yielding and/or flexible strips clamped to the opposed edges of the pane and adapted to be secured in spaced relation to the aforesaid clamps to window opening devices whereby either one of the opposed edges may be moved into spaced relation with respect to the edge of the aperture while the flexible connection at the other edge serves as an articulated joint. Preferably the window opening devices comprise a bolt or bolts passing to the interior of the vehicle and provided with shoulders or lugs adapted to be engaged by manually operable latches whereby the bolts may be moved and retained in predetermined positions with respect to the latch. A further object of the invention is the provision of a hinged connection for a closure which shall eliminate wear and the noise incident thereto as well as the necessity of lubrication. Accordingly the closure is clamped within a groove formed in one edge of a strip of yielding non-metallic material whereof the opposite edge is clamped in spaced relation to the first named point of clamping to that point about which the closure is adapted to swing. In order that the invention may be clearly understood and readily carried into effect the same will now be described more fully with

reference to the accompanying drawings illustrating a preferred embodiment thereof, in which:

Figure 1 is a view in front elevation of the closure for a ventilating port according to the present invention.

Figure 2 is a horizontal longitudinal sectional view taken in the plane indicated by the line 2—2 in Figure 1 and looking in the direction of the arrows and showing the closure and the operating means therefor.

In the drawings a vertically disposed wall section is shown at *a* and a ventilating port or window therein is indicated at *a'*. A closure for the opening *a'* which consists, in the illustrated embodiment, of a pane of glass *b* is shown as engaged upon opposed edges *b'*, *b*² by flexible connections *c*. These flexible connections may take the form of relatively broad strips of material which may be of rubber or suitable layers of fabric secured together in any convenient manner and formed with a groove or the like *c'* adapted to receive the edge of the closure *b*. Upon opposite sides of the strip *c* are disposed plates *c*², *c*² which together with the bolts *c*⁵ passing through apertures in the plates *c*², strips *c* and closure *b* are adapted to clamp the edge of the strip *c* to the edge of the closure *b*. Spaced from the plates *c*² are similarly disposed plates *c*⁴ adjacent the opposite side of the strip of flexible material *c* and spaced from the plates *c*² as will be obvious from an inspection of the drawings. Plates *c*⁴ are secured in clamping relation with respect to the edge of the strip *c* by means of bolts *c*⁵ provided respectively with shoulders *c*⁶ and adjustable nuts *c*⁷ whereby the desired compression may be exerted upon the clamping plates *c*⁴. Bolt *c*⁵ is provided with a head *c*⁸ or other convenient medium for a hand-hold and also with spaced shoulders *c*⁹, *c*¹⁰. Apertures *a*² spaced from the edges of the ports *a'* are provided in the walls *a* for the passage of the bolts *c*⁵ into the interior of the vehicle where they may be conveniently grasped by an occupant.

Adjacent each bolt *c*⁵ is a slide *d* formed with an axial slot *d'* through which one or more wood screws *d*² may pass into the wall *a* while the heads thereof serve as securing means for the slide and permit relative movement thereof. Head *d* may have an inturned portion *d*³ serving as a hand-hold to facilitate manipulation and a bifurcated end *d*⁴

adapted to engage in one position one of the shoulders c^9 or c^{10} on the bolt. If desired the edges of the port may be encircled or surrounded by a resilient cushion e serving 5 as a sealing means for the port when the window is completely closed.

The operation of the device should be apparent from the foregoing description. At the left-hand side of Figure 2 the closure is indicated in closed position wherein the bolt c^5 is drawn inwardly through the aperture a^2 to extreme position and the slide d has been moved so that the bifurcated portion d^4 engages the shoulder c^9 and prevents axial 10 movement of the bolt which would serve to space the edge b^2 of the closure b from the wall a . A similar position is indicated at the right-hand side of Figure 2 in full lines. In dotted lines there is indicated the position 15 of the closure when opened at that end to promote circulation of air. To effect such opening the slide d is first moved to the right, as will be understood, and the bolt c^5 moved axially through the aperture a^2 until 20 the bifurcated end d^4 may engage the groove c^{11} formed between the shoulder c^{10} and the head c^8 to prevent axial movement of the bolt in either direction. The spaced relation 25 of the plates c^4 , c^2 at the left-hand side of Figure 2 afford articulation due to the flexible material of the strip c and similar articulation is afforded if necessary at the right-hand side of the closure.

By the construction just described the 30 closure may be maintained in closed relation with respect to the port or either edge thereof or may be disposed in spaced relation with respect to the corresponding edge of the aperture or, thirdly, both edges of the closure 35 may be maintained in spaced relation from the sides of the port.

It will thus be seen that a particularly 40 practical, convenient and advantageous closure is provided for a ventilating window. Obviously various modifications may be 45 made in the position and configuration of the component elements going up to make up the

closure as a whole as well as any particular form taken by the actuating devices illustrated and no limitation is intended by the foregoing description or drawings beyond that imposed by the claims.

What I claim is:

1. In combination with a wall having an aperture, a closure therefor, flexible strips clamped to opposed edges of the closure, and means engaging said flexible strips whereby either one of opposed edges may be spaced from the wall.

2. In combination with an aperture, a closure therefor, resilient strips clamped along one side to opposed edges of the closure and along the other side to bolts respectively, and means to selectively position said bolts with respect to the aperture.

3. In combination with an aperture, a closure therefor, flexible strips formed with grooves engaging respectively opposed edges of the closure, clamping plates engaging said flexible strips upon opposed faces thereof along one edge of said strip, bolts securing said clamping plates, clamping plates disposed along the other edge of said flexible strips in spaced relation with the first named plates, bolts engaging said plates and formed 70 with shoulders, and latches to selectively engage the shoulders.

4. In combination with an aperture, a closure therefor of transparent frangible material, a strip of rubber formed with a groove for the reception of said closure, clamping plates engaging said rubber strip upon opposed faces thereof adjacent the edge containing the groove, bolts securing said clamping plates and passing through apertures in 85 the closure, clamping plates disposed along the other edge of said rubber strip in spaced relation with the first named plates, and means to secure said last named plates adjacent the aperture.

This specification signed this 4th day of Sept. A. D. 1925.

ALFRED F. MASURY.
